CLAIM

We claim the ornamental design for a charging stand equipped with dust removal for vacuum cleaner, as shown and described.

DESCRIPTION

FIG. 1 is a top, front, right side perspective view of a charging stand equipped with dust removal for vacuum cleaner, showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a top, front, right side perspective view thereof; and,

FIG. 9 is a top, front, right side perspective view of detail “9” identified in FIG. 8, shown enlarged for clarity of disclosure.

The broken lines in the drawings depict portions of the charging stand equipped with dust removal for vacuum cleaner that form no part of the claimed design. The dash-dot-dash lines define the boundaries of the claim.
